(57) **CLAIM**

The ornamental design for an electrical box, as shown and described.

DESCRIPTION

FIG. 1 is a perspective view of the electrical box in accordance with the present invention first embodiment from the front and one transverse side, the transverse side shown being representative of both transverse sides.

FIG. 2 is a perspective view of the electrical box of FIG. 1 from the back and one transverse side, the transverse side shown being representative of both transverse sides.

FIG. 3 is a perspective view of the electrical box of FIG. 1 from the front and one longitudinal side, the longitudinal side shown being representative of both longitudinal sides. FIG. 4 is a perspective view of the electrical box of FIG. 1 from the back and longitudinal side, the longitudinal side shown being representative of both longitudinal sides.

FIG. 5 is an orthographic longitudinal side view of the electrical box of FIG. 1 and defining the section of FIG. 8. FIG. 6 is an orthographic transverse side view of the electrical box of FIG. 1 and defining the section of FIG. 9. FIG. 7 is an orthographic front view of the electrical box of FIG. 1.

FIG. 8 is a perspective transverse section of the electrical box of FIG. 1.

FIG. 9 is a perspective longitudinal section of the electrical box of FIG. 1.

FIG. 10 is a perspective view of the electrical box in accordance with a second embodiment showing the front and one longitudinal side, the longitudinal side shown being representative of both longitudinal sides.

FIG. 11 is a perspective view of the electrical box of the second embodiment of FIG. 10 showing the back and one transverse side, the transverse side shown being representative of both transverse sides; and,

FIG. 12 is a perspective view of the electrical box first embodiment of FIG. 1, claimed portion only, from the front and one transverse side.

In all figures, broken lines depict portions of the electrical box that are environmentally illustrative and form no part of the claimed design. The unclaimed portions are shown as see-through to more clearly depict claimed portions.
